UNITED STATES PATENT OFFICE.

JAY P. WALKER, OF OKLAHOMA CITY, OKLAHOMA, ASSIGNOR TO AMERICAN TANK COMPANY, OF OKLAHOMA CITY, OKLAHOMA, A CORPORATION OF OKLAHOMA.

HATCH FOR FLUID-STORAGE TANKS.

Application filed July 17, 1925. Serial No. 44,249.

This invention relates to new and useful improvements in hatches for fluid storage tanks.

The invention has to do with hatches providing a convenient means for gaining access to the contents of the tank, whereby the latter may be gauged for quantity and a sample for quality taken.

The object of the invention is to provide an efficient and easily and quickly operated fastening for the hatch cover.

A further object is to provide a seal so that unauthorized persons cannot open the hatch.

A further object of the invention is to provide means for supporting the cover in its open position.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side view partly in section and showing a hatch constructed in accordance with my invention,

Fig. 2 is a plan view of the same,

Fig. 3 is a detail of the sealing means, and

Fig. 4 is a detail of the cam and bail connection.

In the drawings the numeral 10 designates a circular collar having an outwardly directed base flange 11 by which it is secured to the tank 12. At the back of the collar is cast a vertical and radial boss 13 extending upwardly from the flange. The boss terminates flush with the top or upper edge of the collar and has a pair of spaced upstanding ears 14.

A circular flanged cover 15 has an arm 16 extending radially therefrom and curved upwardly. A lug 17 depends from the arm at its intersection with cover and is positioned between the ears 14. A hinge pin 18 passes through the ears and the lug. The cover slightly overhangs the collar and has a marginal annular groove 19 in its face, said groove being dove-tail in cross-section. A gasket 20 of suitable elastic material is engaged in said groove and projects below the flange of the cover so as to rest upon

the collar. The cover has a depending central boss 21 depending within the upper end 55 of the collar.

Trunnions 22 project radially from diametrically opposite sides of the collar and an arched bail 23 has its lower ends hinged on said trunnions. The top of the cover 15 60 is spherical and the bail swings over the same. At the center of the top of the bail is formed a yoke 24. A fastening cam 25 has its tip pivoted in said yoke on a transverse pin 26, while a lever 27 extends from the other end of the cam. It will be seen that by swinging the bail to an upright position and pressing down the lever the cam will be wedged against the top of the cover 15, thus fastening it and also compressing 70 the gasket 20, thereby effecting a fluid-tight closure.

At the upper end of the collar I provide a radial ear 28 and the flange of the cover 15 has an overhanging radial ear 29 registering with the ear 28. A seal loop 30 of the non-reusable type is passed through the ears to seal the cover in its closed position. For convenience the ears 28 and 29 may be placed to form stops to arrest the bail in its upright position, but this is not essential. The arm 16 forms a handle or foot treadle which may be depressed to swing the cover to its open position and it constitutes a stop when engaging the flange 11 to limit the 85 upward swing of the cover and to hold the latter in its open position.

Various changes in the size and shape of the different parts, as well as modifications and alterations may be made within the 90 scope of the appended claims.

What I claim, is:

1. In a hatch of the character described, a collar for attachment to a storage receptacle, a cover pivoted on the collar, a sealing ear on the collar, an alined sealing ear on the cover registering with the ear on the collar, and a bail pivoted on the collar, the sealing ears being located to arrest the bail in an upright position.

2. In a hatch of the character described, a collar for attachment to a storage tank, a cover pivoted on the collar, a sealing ear on the collar, an alined sealing ear on the cover registering with the ear on the collar, a bail pivoted on the collar, the sealing ears

being located to arrest the bail in an upright position, and a cam fastening pivoted to the bail and engaging the cover.

3. In a hatch, a collar having a base flange, a boss extending vertically on the outside of the collar with pivoting ears at its top, a cover provided with a cooperating pivoting ear, a radial arm extending from the cover to engage the vertical face of the 10 boss, apertured sealing ears on the collar

and cover disposed to align when the cover is closed, a bail hinged on the collar and swinging over the cover to engage the sealing ears, a cam pivotally retained in a yoke at the apex of the bail and engaging the 15 cover, and an operating lever for said cam.

In testimony whereof I affix my signature.

JAY P. WALKER.
